UNITED STATES PATENT OFFICE.

FREDERICK SCHWATKA, OF ROCK ISLAND, ILLINOIS.

DESIGN FOR A SPOON, &c.

SPECIFICATION forming part of Design No. 20,832, dated June 16, 1891.

Application filed March 28, 1891. Serial No. 386,851. Term of patent 14 years.

To all whom it may concern:

Be it known that I, FREDERICK SCHWATKA, a citizen of the United States, residing at Rock Island, county of Rock Island, State of Illinois, have invented and produced a new and original Design for a Spoon, Ladle, Knife, Fork, &c., of which the following is a specification, reference being had to the accompanying drawing, forming part thereof.

10 The drawing is a front view of a spoon illustrating my design.

The leading feature of my design is a handle emblazoned with or composed of a series of superposed grotesque faces or figures.

15 In the said drawing, A represents the bowl of my spoon or other implement, and B its handle or handle.

1 2 3 4 5 are a succession of grotesque fig-

ures, in relief, superposed one above another. 20 Of the above figures the lowest or that one nearest the bowl is a grotesque figure having a scale-covered body that terminates below in a scroll and above in the head of a bird of prey having exaggerated human-like eyes. 25 2 is a rude human effigy, and 3 a rude representation of a human skull. 4 is a clothed figure, which is surmounted by a grotesque human head having a bird's beak in place of a mouth. 5 represents a human head bearing a hat.

I claim—

The design for the handle of a spoon, &c., substantially as herein shown and described.

FREDERICK SCHWATKA.
